UNITED STATES PATENT OFFICE

165,845

UNIT HEATER

George E. Hughes, Columbus, Ohio, assignor to
Surface Combustion Corporation, Toledo, Ohio,
a corporation of Ohio

Application May 20, 1950, Serial No. 10,075

Term of patent 14 years

(Cl. D81—10)

To all whom it may concern:

Be it known that I, George E. Hughes, a citizen of the United States residing at Columbus, in the county of Franklin and State of Ohio, have invented a new, original, and ornamental Design for a Unit Heater, of which the following is a specification, reference being had to the accompanying drawing forming a part hereof.

Fig. 1 is a front perspective view of a unit heater embodying my new design.

Fig. 2 is a rear perspective view of the heater.

Fig. 3 is a top plan view of the heater.

I claim:

The ornamental design for a unit heater, as shown.

GEORGE E. HUGHES.
